COOLING SYSTEM FOR GAS TURBINE
BLADING

Ernest Lagelbauer, New York, N. Y.

Application May 29, 1947, Serial No. 751,164

2 Claims. (Cl. 60—39.16)

1

My invention relates to gas turbines and, more specifically, to a unique and novel method for cooling the blading of a turbine that is normally exposed to gases of extreme temperatures.

My principal objective is to provide an arrangement for cooling the turbine blading whereby the turbine may be safely operated with gases at exceedingly high temperatures. Such a method not only enables the use of extraordinarily high initial temperatures, but also allows the efficient utilization of the heat that is abstracted in cooling the turbine blades.

A further feature is that the principal disadvantages of up-to-date gas turbine plants, namely the insufficient magnitude of the available adiabatic expansion gradient and the detrimental low permissible heat intake temperature are to a large extent overcome by my method.

Additional features and advantages of my cooling method will be apparent as I proceed with the description.

With reference to the drawings—

Fig. 1 shows a schematic diagram of a dual gas turbine system incorporating my turbine blade cooling method;

Fig. 2 shows a partial sectional view through the primary turbine blading;

Fig. 3 shows a transverse sectional view through the turbine blading; and

Fig. 4 shows a view similar to Fig. 2 of a modification of my invention.

In Fig. 1 I have shown a schematic diagram of a dual gas turbine system incorporating my turbine blading cooling method. Briefly, the component parts of this system, which may be adapted to either aircraft, locomotive or other similar types of load, are as follows:

The high speed single or two stage partial admission gas turbine 10 drives a low pressure stage air compressor 11 and a high pressure stage air compressor 12. Between the low pressure compressor 11 and the high pressure compressor 12 is an inter-cooler 13 for maintaining the temperature of the air 60 taken in by the low pressure stage 11 at a low level. The combustion air 61 delivered by the high pressure stage 12 is conveyed through passage 14 through a regenerator 15 where it is preheated by the exhaust of turbine 20 and thence to the continuous pressure combustion vessel 16. Fuel pump 17 sprays fuel 66 at the suitable rate into the combustion vessel 16 and the formed combustion gases 62 are directed through the expansion nozzle 18 upon the turbine blading 19.

A low speed multistage complete admission turbine 20 which is energized by the exhaust 63

of the primary turbine 10 drives a load 21 through a reduction gear 22. In addition, another turbine 23 of suitable design may be used for driving an additional low pressure stage air compressor 24 for supplementing the air 60 delivered by the low pressure compressor 11. The intermediate pressure gas discharge 63 of turbine 10 is conveyed through duct 25 to a diverter regulator 26 which has the function of apportioning the power gases 63 between turbines 20 and 23 or, in the event of emergency, to release the power gases 63 through duct 27 to the atmospheric exhaust 64. Diverter 28 has the purpose of regulating the air flow division between further compression by compressor 12 and employment in the secondary power cycle of turbine 10 in effecting the cooling of its blading 19 and the subsequent utilization of the acquired available energy content.

20 A pressure adjuster 29 is used to equalize the delivery pressure of compressor 24 with that of compressor 11. Also indicated is a starting motor 30 for furnishing the initial rotating impulse to the turbine 10 and compressors 11 and 12.

25 This system is designed to allow operation with extraordinarily high turbine intake temperatures in allowing low combustion air rates, i. e. restricting air dilution of the combustion gases to the largest permissible extent, and with radically higher compression ratios. Such design characteristics are rendered possible owing to the application of a novel system of cooling those turbine blades which are exposed to gases of extreme temperatures, and to the division of the turbine system into a high speed single stage partial admission turbine and one or more lower speed full admission turbines. In any event the high speed turbine 10 drives the air compressors 11 and 12 which together are allowed to rotate at extremely high speeds, (over 20,000 R. P. M.). This latter feature besides tends towards space and weight economy of the power plant.

40 45 The ultra high speed turbine 10 driving the main air compressors 11 and 12 is designed to operate at a maximum rotational speed allowable with respect to mechanical stresses due to centrifugal forces generated. Consequently, design considerations dictate development of this turbine as a one or two pressure stage action, partial admission type; of course, its bladings 19 may be designed to have some reaction. The turbine nozzle 18 expands the combustion gases 62 as delivered by the continuous pressure com-

bustion vessel 16 at a pressure of about twelve atmospheres or more down to the intermediary back pressure between high pressure turbine 10 and the low pressure turbine 20; that is, to a pressure of 2 to 6 atmospheres, which is the intake pressure for turbine 20. Turbine 20 drives the performance load 21, for instance a locomotive, and in turn exhausts at atmospheric pressure.

The low pressure turbine 20 is designed as a multistage, complete admission type containing several pressure stages and suitable velocity stages. In order to restrict the size and weight of this turbine to advantageous proportions in, for instance, aerial application, a reduction gear 22 is interposed between the turbine 20 and the load 21 and the speed reduction ratio is one determining factor as to the number of stages used in the turbine 20. In design, a suitable compromise is to be struck between turbine diameter, number and kind of stages and the reduction ratio of the gear in accordance with the particular application.

The employment of an additional low pressure air compressor 24 driven either by turbine 20 directly or by a supplementary turbine 23 shown in Fig. 1 is optional but recommended for achieving highest efficiencies. This compressor simply relieves the load demand on the turbine 10.

An outstanding feature of the recommended turbine system is the internal cooling of the high pressure turbine 10 by compressed air.

This method affords several important advantages. It makes practicable the use of extraordinary high initial gas temperatures and allows efficient utilization of the heat abstracted in cooling the turbine blades 19. It also eliminates the detrimental effect of partial admission adopted for the high pressure turbine 10. It provides complete employment of the otherwise only partially active impulse wheel 32 and consequently greater benefits from the respective machinery investment. It allows the application of exceedingly large expansion gradients in the primary turbine cycle, owing to the small combustion air rate practicable in the primary cycle, and to some extent, in the secondary turbine cycle, owing to the dynamic boost imparted to the cooling air 65 in the primary turbine 10. It should be noted that in this process the heat released at combustion and taken into the thermodynamic process at extraordinary high temperature is subjected to a nearly continuous temperature gradient. The irreversible temperature drop occurring in the primary turbine 10 is rather small and its detrimental effect thermodynamically insignificant, as can be visualized readily by inspection of a temperature-entropy diagram. The method also provides ample augmentation of the mass flow through the low pressure turbine 20 in a thermodynamically highly efficient manner.

This method of internal cooling is illustrated diagrammatically by Figs. 2, 3 and 4. It consists in passing precompressed air 65 through that sector 31 of the turbine wheel 32 which is not occupied by the jet of power gases 62. Thus, while the blades 19 are heated in passing through the sector 34 of Fig. 3 occupied by the exceedingly hot power gases 62, they are cooled down again as they pass through the stream of cooling air 65 in sector 31 of Fig. 3. Consequently, the blades 19 are maintained at a temperature much lower than that of the combustion gases 62. In this process the cooling air 65 is energized by the turbine wheel 32 acquiring, in addition to heat, a boost in velocity as well as in pressure. With

regard to the further mechanical utilization of the heat thus absorbed the air pressure rise effected should be promoted by design and as far as possible to take place before the absorption of the heat.

Two modifications of this blade cooling system are available. The one of these illustrated by Figs. 2 and 3 is distinguished by simplicity. The secondary air taken from the low air compressor stages 11 and 24 of Fig. 1 enters the turbine blading 19 near the root and, due to appropriate guiding and to centrifugal action, passes over the blades 19 in approximately radial directions. Thereby it is heated in cooling the blades 19 and brought up to a higher velocity potential. From the turbine wheel 32 the air enters a stage of stationary guide blades (not shown in Fig. 2) which guide the air flow smoothly into the duct 25 leading to the low pressure turbine 20 which utilizes the energy acquired by the cooling air in passing through the turbine wheel 32. In addition, the guide blades mentioned may be so shaped and positioned as to act as diffuser; that is, to convert the acquired velocity potential partially into pressure. In such a design an advantageous balance must be struck between losses related to the diffuser action and the subsequent re-expansion in turbine 10 on the one hand and the advantage gained by the accomplished pressure rise and reduction of flow velocity on the other. This advantage consists in that the cooling air 65 needs to be compressed by the air compressor only to a correspondingly lower initial pressure, for at any rate, the secondary air must leave turbine 10 at the same back pressure as the power gases, which is the intermediary back pressure; or with the same air compression ratio, a higher intake pressure for turbine 20 is achieved. The secondary action of the cooling air amounts to a reduction of the power input to the air compression equipment and a correspondingly increased power flow to the turbine 20. This circumstance affords an important means for effecting load apportionment between turbine 10 and turbine 20, namely, by varying the air flow rate in the cooling air 65 cycle. It should be noted that the pressure within the turbine casing 35 of turbine 10 is very nearly that of the intermediary pressure or back pressure against which the turbine 10 discharges.

A modification of my cooling method is shown in Fig. 4. This method employs a distinct compressor stage 40-41, integral with the turbine 10. The impeller blading 42 is mounted on the turbine shaft 43 ahead of the turbine wheel 44 and imparts mechanical energy, derived from the turbine cycle through the turbine shaft 43 to the cooling air 65 delivered at intermediary pressure level by the regular air compressor 11 through duct 14. The acquired velocity potential is then partially converted into pressure energy in passing through the appropriately designed blading 46 provided for the cooling air 65 and which is a part of the compressor stage 40-41; the blades 46 also guide the air 65 so as to enter the turbine wheel 44 closely in the direction of the leading edge of the blades 45 which, of course, is of importance with regard to avoiding shock losses. In cooling the blading 45 the secondary air 65 therefore absorbs heat at a considerably higher pressure level than in the alternative method described above. Again, the pressure level of the heat intake decidedly determines the thermal efficiency of utilization of the heat.

The primary advantage of this latter method is that it enables absorption of the heat by the cooling air 65 at a higher pressure level throughout, that is, considerably above the intermediate back pressure between turbine 10 and turbine 20. It will be noted that in the more primitive method indicated above, most of the cooling heat is absorbed merely at the intermediate back pressure, if indeed, not slightly below it, and, particularly that the heat due to cooling of the turbine blades is absorbed before any occurring pressure rise, whereas, it is imperative thermodynamically that the pressure rise precede the heating.

The second important advantage of this alternative is the gas dynamic refinement achieved. Particularly, it should be observed that in the more primitive method described above, there is some interference between the jet of combustion gases 62 traversing through the turbine blading 45 essentially in axial direction and the stream of cooling air 65 which flows through the turbine blading 45 in more or less radial directions. Besides, the difference of the absolute velocity of the combustion gases 62 and of the cooling air 65 is greater. The interference results in exchange of momentum between the combustion gases 62 and the cooling air 65 with the consequence of corresponding energy degeneration. Such losses increase with the involved velocity difference.

Another possibility of arrangement is similar to the method as pointed out above, but eliminates the auxiliary booster impeller 43. This modification is marked by greater simplicity but lower efficiency as compared with the second method.

Necessarily, the combustion gases 62 and the heated cooling air 65 leave turbine 10 at a common intermediary exhaust pressure although they differ considerably in temperature. Nevertheless, since the content of available energy is not affected materially during the intermixture of gases of equal pressure but of moderately different temperature level, maintenance of the separation of the combustion gases 62 and of the heated cooling air 65 is not warranted, particularly in view of the machinery complications which would be involved.

The gas discharge of turbine 10 which is of a pressure level of 2 to 6 atmospheres is conducted into turbine 20 and possibly to an eventually employed turbine 22, Fig. 1. The employment of regeneration, such as indicated in Fig. 1 by regenerator 15 and duct 14 is an obvious device for improving the heat economy through pre-heating the combustion air 61 by waste heat. Yet, in instances of turbine applications where extreme machinery weight reduction is a supreme factor, these devices may be omitted, of course at the cost of a corresponding impairment of the overall fuel economy.

It is emphasized that the described dual gas turbine system with cooling the blades of a primary ultra speed gas turbine is applicable to whatever working substance employed, for instance steam, and furthermore may be applied for closed gas or steam turbine cycles such as become of extraordinary importance for efficient utilization of atomic energy for power generation.

While the invention has been described in detail with respect to a present preferred form which it may assume, it is not to be limited to

such details and form since many changes and modifications may be made in the invention without departing from the spirit and scope of the invention in its broadest aspects. Hence, it is desired to cover any and all forms and modifications of the invention which may come within the language or scope of any one or more of the appended claims.

I claim:

- 10 1. In a power system, a rotatable shaft, a turbine wheel thereon having a plurality of blades rotatable in an annular path, an impeller wheel on said shaft adjacent the turbine wheel and having blades thereon, means to pass compressed cooling air into contact with said blades of the impeller wheel, means to pass combustion gases into contact with the exterior surfaces of said turbine blades throughout a predetermined segment of said annular path, fixed blades positioned between the impeller wheel and turbine wheel to guide the compressed air into contact with said exterior surfaces of the turbine blades throughout the remaining segment of said annular path.
- 15 2. A power system comprising a high pressure turbine and a low-pressure turbine, said high pressure turbine being mounted on a rotatable shaft and having a plurality of blades rotatable in an annular path, a low pressure compressor and a high pressure compressor mounted on said shaft, a combustion vessel connected to the high pressure compressor, means for passing fuel and high pressure air into the combustion vessel to form combustion gases and then to the high pressure turbine into contact with the exterior surfaces of said turbine blades throughout a predetermined segment of said annular path, means to pass compressed cooling air from said low pressure compressor into contact with said exterior surfaces of the turbine blades throughout the remaining segment of said annular path, thereby cooling the blades and heating the compressed air, and means to pass the mixture of combustion gases and compressed cooling air to said low pressure turbine to serve as a thermodynamic working substance.
